CLAIM

The ornamental design for a casing assembly for an electrical connector, as shown.

DESCRIPTION

FIG. 1 is a perspective view of a casing assembly constructed in accordance with teachings of the invention.

FIG. 2 is an end elevational view of the casing assembly of FIG. 1.

FIG. 3 is a top plan view of the casing assembly of FIG. 1.

FIG. 4 is a rear view of the casing assembly of FIG. 1.

FIG. 5 is an end view of the casing assembly of FIG. 1 opposite to the end view shown in FIG. 2.

FIG. 6 is a left side view of the casing assembly of FIG. 1; and,

FIG. 7 is a right side view of the casing assembly of FIG. 1.
